OTTO KAMPFE, OF BELLMORE, NEW YORK, ASSIGNOR OF ONE-HALF TO HENRY C.
WALKER, OF BOSTON, MASSACHUSETTS.

TOOL.

1,334,100.

Specification of Letters Patent. Patented Mar. 16, 1920.

Application filed March 14, 1919. Serial No. 282,631.

To all whom it may concern:

Be it known that I, OTTO KAMPFE, a citizen of the United States, residing at Bellmore, in the county of Nassau and State 5 of New York, have invented an Improvement in Tools, of which the following is a specification.

This invention relates to an improved tool, and is designed for use both as a can 10 opener and as a tool for removing bottle caps. The general construction of tools for opening cans as now commonly employed consists of a blade and a guard placed adjacent thereto to act as a lever for cutting the 15 cover of a can by drawing the knife blade through the same after the knife blade has been used as a punch to make the hole in the can. In these can openers therefore, the point of the knife blade as commonly 20 constructed extends appreciably beyond the end of the guard so as to permit the use of the point of the knife blade in puncturing the can. Obviously, in the use of an implement so constructed, the full length of 25 the blade cannot be utilized in making a cut in the can, and furthermore the point of the blade is normally unprotected. The object of my invention therefore is to overcome these difficulties by providing an instrument 30 adapted for use primarily as a can opener and in which, together with a handle, there is provided a knife blade and a movable guard adapted normally to extend beyond the point of the knife blade 35 and to be movable so that the point of the knife blade may be employed to puncture the can, when as will be understood the lever may be returned to its normal position and by extending beyond the point of the 40 blade makes it possible to employ the full length of the blade in making each cut in the can. Furthermore as hereinafter indicated, the tool is provided with a hooked 45 extension also adapted to coöperate with the guard or lever so as to be utilized as an instrument for removing bottle caps.

In the drawing:

Figure 1 is a side elevation of the tool made in accordance with my present invention.

Fig. 2 is an inverted plan of the same,

Fig. 3 is a plan of the same,

Fig. 4 is a view similar to Fig. 1 showing another form of the invention, and

Fig. 5 is a plan of the same.

Referring to the drawing and particularly to Figs. 1 to 3 inclusive, in carrying out my invention, I prefer to employ a handle which may be made in parts as indicated at 10, and between which a plate 11 is suitably fixed. The plate 11 extends beyond the end of the handle members and terminates in a knife blade 12. In suitable positions on this plate 11 I also provide a lateral extension 13 which terminates in a hooked end 14.

Associated with the parts hereinbefore described, I also employ a guard which is preferably composed of two members 15 and 16 of similar configuration and pivotally connected in the plate 11 as indicated at 17. The parts of the guard furthermore are connected at one end by a rivet or pin 18 on which is also mounted between the members of the guard a roller 19, while at the opposite ends the members 15, 16 of the guard are also riveted together as indicated at 20 with an intervening spacer member 21. As is plainly indicated in the drawing, the members 15, 16 of this guard lie on opposite sides of the plate 11.

Adjacent the inner or handle end of the members 15, 16 of the guard the same are recessed as indicated at 22 in order to receive a cam member 23 which lies within the said recesses and is pivotally connected to the plate 11 as indicated at 24. The cam member 23 is fitted with a handle 25 by which the same is operated and which handle normally lies against the edge faces of the handle members 10. Adjacent the outer ends of the handle members 10, the plate 11 is provided with a recess 21' in the edge thereof to receive the spacer 21 when the guard member is at its normal position as shown in Fig. 1.

In the use of the hereinbefore described tool, the handle 25 is swung outwardly in the direction of the arrow to cause the handle to assume the position shown in dotted lines in Fig. 1, when as will be understood, the guard member may be turned on its pivotal point to also assume the position shown in dotted lines in Fig. 1. When in this position, the point of the blade may be used to puncture the top of the can to be opened. After this is done, the guard member is turned so that the cam 23 will enter the recess 22 and may be turned by the handle 25 in returning the same to the full line 110

position shown in Fig. 1, so as to lock the guard in place, when, as will be understood, the point of the blade may be inserted again in the hole made in the can and the tool used as an ordinary can opener. In so doing, the forward end of the guard member acts as a lever against which the cut is made, and inasmuch as this lever extends appreciably beyond the point of the blade, the entire length of the blade may be utilized in making each cut in the can. Furthermore as will be readily understood, the opposite side of the forward end of the guard member acting in conjunction with the hooked end 10 of the extension 13 may be employed as a tool for removing bottle caps.

By referring to Figs. 4 and 5, it will be seen that instead of mounting the guard member so as to swing on the blade forming 20 part of the tool, this guard member may be merely slidable thereon from one position to another so as to normally lie extended beyond the point of the blade to extend therefrom sufficiently far to permit 25 the point of the blade to be used to puncture a can to be opened. In these figures of the drawing, the parts of the guard member are indicated at 26 and 27. At the forward end they are connected by a rivet in the same 30 manner as the guard member hereinbefore described. In each of these parts of the guard member, there are similarly placed slots 28 adapted to receive pins 29 fixed in the opposite faces of the plate 11 so that 35 as will be understood, the guard member

may be moved along the plate from the position shown in full lines to that indicated in dotted lines in Fig. 4. In this construction of the invention, the extension 13 is provided with a pawl 30 which is pivotally connected thereto as indicated at 31 and the tooth of the pawl is adapted to enter a notch 32 in the edges of the parts 26 and 27 of the guard member to maintain the same in its operative position as shown in Fig. 4, this being done as will be understood by the user placing his thumb against the surface of the pawl to maintain the same in place.

I claim as my invention:

1. A tool of the class described, a knife blade, a guard member pivotally connected to the knife blade, and a cam member also pivotally connected to the knife blade and adapted to move in a recess provided therefor in the guard to lock the same in its normal operative position.

2. In a tool of the class described, a knife blade, a two-part guard member spanning the said knife blade and pivotally connected thereto with the forward end of the guard member normally extending an appreciable distance beyond the point of the knife blade, and a cam member also pivotally connected to the said blade and adapted to move in recesses provided therefor in the parts of the said guard to lock the same in a normal operative position.

Signed by me this 11th day of March, 1919.

OTTO KAMPFE.
